ABSTRACT OF THE DISCLOSURE

A system for anchoring a flexible element in a subsurface well whereby geological-investigation instruments can be guided into the well along the flexible element and wherein the anchor has a blade receivable in a retrieval sleeve while pawls are spring-biased outwardly on the blade so as to be cammed inwardly when the blade is inserted into the sleeve. When it is desired to retract the anchor, the blade engages the sleeve via the pawls. One or more spacer rods serve to maintain the sleeve and anchor in spaced relationship for advance of the anchor system into the bore whereby the pawls engage the wall of the bore for normal cable anchoring prior to retrieval.

Our present invention relates to improvements in geological subsurface investigations and, more particularly, to a system for temporarily anchoring a flexible element in a subsurface bore for the guidance of geological instruments therein as well as to an improved method of investigating such bores.

Background of the invention

It has already been proposed to provide for the geological investigation of subsurface bores retrievable anchors for flexible elements such as wires or cables used to guide the instruments into and along such bores. For this purpose, an anchor assembly of triangular section has been employed whose forward end is provided with three outwardly swingable claws controlled by a sheave around which the flexible element is passed. By proper movement of the flexible element the claws can be retracted and the anchorage of the device released so that the system can be returned to the mouth of the bore. In practice, however, such arrangements have proved to be generally unsatisfactory, especially when the geological-exploration bore (e.g. for geological, geophysical, petrochemical, petrophysical, prospecting, and like investigations) has a diameter of 70 mm. or less and is inclined to the vertical. In such cases it has been impossible to make use of these conventional anchors and, while other expedients have been suggested, none have proved to be effective.

Objects of the invention

It is, therefore, the principal object of the present invention to provide a system for temporarily anchoring a flexible element and a geological-exploration bore which can be used effectively even in small-diameter bores and which can be recovered with facility therefrom.

Another object of this invention is to provide an improved system of the character described which is readily recoverable without damage from a geological-exploration bore, which is of simple and inexpensive construction, which is free from tendency to malfunction and which can be set up for reuse rapidly and with ease.

Still another object of our present invention is to provide an improved method of investigating geological-exploration bores and especially bores of relatively small diameter.

Brief summary of the invention

These objects and others which will become apparent hereinafter are obtained in accordance with the present invention by an improved method of investigating a subsurface bore with geological-investigating apparatus guided therein by a flexible element controlled from the mouth of this bore which has a diameter of, say, less than 70 mm. and is inclined to the vertical (e.g. is of horizontal or oblique orientation); the method comprises essentially the steps of inserting into this bore a rearwardly open and preferably forwardly closed retrieval sleeve and, following said sleeve, an anchor for the flexible element having at least one outwardly biased pawl engageable with the wall of the bore to prevent withdrawal of the anchor, the movement of this anchor being terminated short of the sleeve. Thereafter, the apparatus is guided into the bore with the aid of this flexible element and, upon conclusion of the geological investigation, the system including the anchor and the sleeve is withdrawn. The withdrawal operation is carried out by shifting the anchor forwardly into the sleeve so that at least this pawl is received therein and lodges against the sleeve to lock the latter to the anchor; thereafter, both anchor and sleeve are retracted from the bore by drawing them therefrom with the flexible element.

According to another feature of this invention, the sleeve and anchor are advanced into the bore jointly, although in sequence and in longitudinally spaced relation, by a pusher head which may be mounted upon some form of pusher means (e.g. the drill string or rod provided for this purpose) the head having spacer means extending past said anchor into engagement with the sleeve. The anchor has a forward blade portion carrying a multiplicity of such pawls and flanked by the spacer means (e.g., two spacer rods) so that the entire assembly can be accommodated in relatively small diameter bores.

Although the features and advantages are set forth in detail below, it will be readily recognized that the harpoon-like system of the present invention with its sword-like blade portion carrying the pawls on opposite sides of the blade, affords a positive disengagement of the anchor from the walls by further forward movement of the anchor while the sleeve is relatively immovable. When the blade portion is fully housed in the sleeve, it retains all of the pawls out of engagement with the walls of the bore so that the sleeve acts as a sheath for the sword-like portion and the most sensitive part of the apparatus, namely, the resiliently biased pawls. Furthermore, the sleeve serves to move detritus ahead of its closed end so that loose material cannot block operation of the pawls following the sleeve.

We have also found it to be most advantageous when the pusher head is provided with means, e.g. an eye, for returning an end of the flexible element to the mouth of the bore, as well as with abutments for preventing swinging movement of the pawls in their "opening" motion through an angle of more than 90°. The open rearward end of the sleeve thus is able to cam the pawls inwardly as the anchor is moved into the sleeve by the subsequent pushing operation prior to retrieval of the system. The sleeve can be provided at this open end with an inwardly extending annular flange in the form of a locking ring which is engaged by the rearmost pawl to lock the sleeve to the anchor and enable both to be withdrawn together from the bore. Release of the sleeve from the anchor is permitted by openings adjacent this locking ring whereby a tool can be inserted to disengage each pawl from the ring and enable the sleeve and anchor to be drawn apart.

Description of the views of the drawing

The above and other objects, features and advantages of the present invention will become more readily ap-

parent from the following description, reference being made to the accompanying drawing in which:

FIG. 1 is a longitudinal section of the harpoon device in the process of being pushed into a subsurface bore;

FIG. 2 is a longitudinal section of the anchor harpoon, seated in its retrieval sleeve, in condition for withdrawal from the bore or subsequent to such withdrawal;

FIG. 3 is a cross-sectional view taken along the line III—III of FIG. 1; and

FIGS. 4 and 5 are cross-sectional views taken respectively along the lines IV—IV and V—V of FIG. 1.

Detailed description

The retrieval sleeve of the present invention, as shown in the drawing, comprises a tube 2 and a lock ring at its open end or mouth, the purpose of which will become evident hereinafter. The sleeve is inserted into the subsurface bore, e.g. a geological-exploration hole, in advance of the anchoring harpoon H which, as seen in FIGS. 1 and 2, comprises a blade 4 carrying a plurality of longitudinally spaced pawls 9; the latter are pivoted on rivets 6 attached to the blade 4 on opposite sides thereof. Further, the blade 4 carries abutment bolts or studs 5 which limit to acute angles (less than 90°) the outward swinging movement of the respective pawls 9, and torsion springs 10 in recesses 7; the springs engage at one end in apertures 8 of the blade 4 and resiliently bias the pawls 9 outwardly at the other end of each spring.

The blade portion 4 extends axially into a tube portion 12 at the rearward end of the anchor and is affixed to this tubular portion at 11, e.g. by welding; a return or idler roller, pulley or sprocket 14 is journaled within the tubular portion 12 on a diametrically extending pin 13 which may be generally coplanar with the blade portion 4 of the anchor H. The tubular portion 12 has angularly offset pairs of semicircular openings 15 and 15' in its end plate 16 (FIG. 4). Through one of these openings a rope, cable, wire, chain or other flexible element 17 passes into the tubular portion 12, around roller 14 and out through the other opening 15'; the flexible element 17 extends through the bore, drilled by conventional techniques for geological investigation (e.g. for oil or mining exploration and prospecting) with the usual coring drill or drill string.

One end of the flexible element 17 is preferably attached to an eye 21 of a rod head 23. Two parallel spacing rods 20, affixed to the rod head 23 (cf. FIG. 5) are adapted to bear against the retrieval sleeve 2 when the latter is disposed forwardly of the rod head in the direction of insertion. The spacing rods 20 slide through the openings 15' (or the openings 15 alongside the roller 14) and bypass the roller, while flanking the blade 4. At the same time, a guide rod 18 is received in the hollow rod head 23 so that an abutment pin 19 thereof lies in a notch 22 of the rod head. With forward movement of the head 23, the rods 20 are slid into the retrieval sleeve 2 through the lock ring until they rest against the closed end of the sleeve 2. The guide rod 18 is rigidly attached to the plate 16 at the rearward end of the anchor H and extends rearwardly therefrom into the head 23 or the tubular drill string 24 serving as a pusher so as to ensure alignment of the assembly during insertion of the anchor H into the bore as well as during its movement subsequently into the sleeve by the pusher string.

The rod head 23, which is removably fastened to the pusher rod or drill string by a threaded sleeve 26, serves to advance the retrieval sleeve 2 and the anchor harpoon H in succession, but simultaneously and jointly, into the subsurface bore. When the pusher is withdrawn with its head 23, the spacing rods 20 pull out of the retrieval sleeve 2 and the anchor harpoon H. The end of element 17, which is fastened to eye 21, is carried along with the head 23 to the entrance of the bore. There, observation and measurement instruments 27, e.g. radiation detectors, cameras,

temperature-measurement devices, are attached and guided forwardly and backwardly with the flexible element 17. When this investigation is completed, the pusher string may be reinserted into the bore without its rod head 23, guided against the abutment pin 19 by the rod 18, and brought to bear against the anchor H. Blade 4 of the harpoon is now shifted further forwardly and into the retrieval sleeve 2 which has become immobilized at the end of the bore, has been blocked by detritus accumulated in front of the closed end 1, or has been merely restrained against forward movement by its extensive frictional contact with the wall of the bore.

The pawls 9 are cammed inwardly and disengaged from the walls of the bore against which they had taken an anchorhold during withdrawal of the rod head 23 and upon the application of traction to the element 17 fastened to the head. The outwardly biased hindmost pawl 9 becomes locked against the front end of the sleeve at the ring 3, which constitutes an inwardly extending annular flange, since the tip 3' of this pawl cannot slide back over the ring. All of the pawls 9 are urged against the tube wall by the springs 10 and are held thereby out of engagement with the wall of the bore.

Thus tension applied to element 17 in the rearward direction (arrow 28) brings back the harpoon H as well as the retrieval sleeve 2, locked to the blade 4. Outside the bore, pawls 9 are pressed inwardly (arrow 29) through two opposite openings 25 of the retrieval sleeve 2 immediately in front of the lock ring 3, whereby the blade 4 can be gradually removed from the sleeve 2. A pin 30 may be used for this operation.

The invention described and illustrated is believed to admit of many modifications within the ability of persons skilled in the art, all such modifications being considered within the spirit and scope of the appended claims.

We claim:

1. A method of investigating a subsurface bore with geological investigation apparatus guided therein by a flexible element, comprising the steps of:

(I) inserting into said bore a rearwardly open retrieval sleeve;

(II) thereafter inserting into said bore an anchor having at least one outwardly biased pawl engageable with the wall of said bore preventing withdrawal of said anchor, and terminating the movement of said anchor into said bore short of said sleeve, said flexible element being affixed to said anchor and extending within said bore;

(III) guiding said apparatus into said bore and removing it therefrom with said flexible element; and

(IV) subsequently withdrawing said anchor and sleeve from said bore by

(a) shifting the anchor forwardly into said sleeve to lodge at least said pawl therein with said sleeve holding said pawl out of engagement with said wall and said pawl locking said sleeve to said anchor, and

(b) retracting said anchor and said sleeve jointly from said bore by drawing said anchor therefrom by said flexible element.

2. The method defined in claim 1 wherein said sleeve and said anchor are inserted into said bore in steps (I) and (II) by shifting them jointly therein in spaced relationship.

3. A system for anchoring a flexible element in a subsurface bore, comprising a rearwardly open retrieval sleeve insertable in said bore; an anchor for said flexible element, said element being affixed to said anchor, said anchor being insertable into said bore behind said retrieval sleeve for temporarily retaining said flexible element in said bore, said anchor having a forward blade portion receivable in said sleeve, at least one outwardly biased pawl on said blade portion engageable with the wall of said bore to prevent withdrawal of said anchor in the direction of the mouth of said bore, said pawl being cam-

mable inwardly upon advance of said blade portion into said sleeve and lockable thereto for entraining said sleeve with said anchor for retraction of the system from said bore; and means maintaining said sleeve and anchor in spaced relationship during joint advance thereof into said bore.

4. A system as defined in claim 3 wherein said anchor has a tubular portion affixed to and rearwardly of said blade portion, and roller means in said tubular portion, said flexible element passing around said roller means, said retrieval sleeve having an inwardly extending flange at its open end engageable by said pawl upon insertion of said blade portion into said sleeve.

5. The system defined in claim 3, further comprising pusher means for advancing said retrieval sleeve and said anchor jointly into said bore in spaced relationship.

6. The system defined in claim 5 wherein said pusher means includes a pusher head mounted upon a drill string, and said means maintaining said sleeve and anchor in spaced relationship comprising at least one spacer rod extending longitudinally from said head and flanking said blade portion while bearing upon said sleeve for advancing the latter into said bore upon movement of said head in a forward direction.

7. The system defined in claim 6 wherein said anchor has a rearwardly extending guide rod received in and engageable with said head for shifting said anchor through said bore upon advance of said head in said forward direction.

8. The system defined in claim 6 wherein said head is provided with means for drawing said flexible element from said anchor to the mouth of the bore upon retraction of said head from said bore.

9. The system defined in claim 3, further comprising roller means carried by said anchor and guiding said flexible element, and geological instrumentation guidable in said bore by said flexible element.

10. The system defined in claim 3 wherein said anchor has a rearwardly extending tubular portion affixed to said blade portion, an idler roller journaled in said tubular

portion for guiding said flexible element therearound, a plurality of said pawls pivotally mounted on opposite sides of said blade portion in longitudinally spaced relationship, a respective torsion spring acting upon each of said pawls for resiliently biasing same outwardly into engagement with the wall of said bore, and a respective abutment engageable with each of said pawls for limiting the outward pivoting movement thereof to an angle less than 90°; said sleeve having a closed forward end for the displacement of detritus before it upon its insertion into said bore, and an inwardly projecting lock ring at its open end, said sleeve being provided with an opening adjacent said lock ring for permitting said pawl to be disengaged from the lock ring upon separation of said anchor from said sleeve; said system further comprising a pusher head mountable upon a drilling string for jointly advancing said sleeve and said anchor into said bore in longitudinally spaced relationship, said pusher head having a pair of parallel forwardly extending spacer rods adapted to pass through said tubular portion and flanking said blade portion while bearing upon said retrieval sleeve for forward movement thereof, said head having a forwardly open recess, said anchor having a rearwardly extending guide rod at least partly receivable in said head and an abutment pin adapted to be lodged in said recess for forward movement of said anchor.
